PERCUSSIVE DEVICE

Application filed July 27, 1927. Serial No. 208,811.

My invention relates to percussive devices and particularly to such devices wherein a periodic force is utilized to actuate a hammer head.

5 One object of my invention is to provide a percussive device wherein the several parts and the forces utilized for actuating the parts are so related to each other as to secure stable operation of the device and produce impacts of maximum intensity in an efficient manner.

10 Another object of my invention is to make devices of the above-described character wherein the frequency of the blows of the percussive device will be a fraction of the 15 frequency of the periodic force acting upon the hammer head.

A further object of my invention is to provide percussive devices that will operate in a stable manner, notwithstanding slight variations of the conditions of operation and the constants determining the operating characteristics.

I have found that a very efficient and simple percussive tool for chipping, riveting, etc., 25 may be constructed by combining a hammer head adapted for reciprocal motion with a suitable energy-storing means, such as a spring, for biasing the same towards an anvil or tool holder, and electro-magnetic means 30 for periodically lifting the hammer head from the anvil, provided that the several elements constituting the mechanical oscillating system so obtained have certain definite relations to each other and to the periodic, 35 externally-impressed force acting thereon.

The foregoing and other objects of my invention will be best understood by reference to the accompanying drawings, wherein

Figure 1 is a view, partially in section and 40 partially in elevation, illustrating a hammer of the single-solenoid type to which my invention is applied,

Fig. 2 is a view, similar to Fig. 1, illustrating a hammer of the double-solenoid type, 45 embodying my invention,

Fig. 3 is a circuit diagram illustrating the connections of the solenoid coils employed in the device shown in Fig. 2,

Fig. 4 is a diagrammatic view of the elements constituting the mechanical oscillat-

ing system of the devices shown in Figs. 1 and 2, and

Figs. 5 and 6 are graphical diagrams illustrating various relations between the elements effecting the operation of the percussive devices shown in Figs. 1 and 2.

55 My invention will be explained as applied to a solenoid-operated device either of the type using a single energizing solenoid, as shown in Fig. 1, or one using a double energizing solenoid, as shown in Fig. 2.

60 Referring to Fig. 1, a longitudinally disposed cylindrically-shaped plunger or hammer head 1, of magnetic material, is mounted for reciprocal movement within a non-magnetic cylindrical guide member 2 that is held within a hollow cylindrical casing 3 of magnetic material. The hammer casing 3 is provided, at its top portion, with a suitable handle 4 which may be gripped by the operator. 65 At its lower end, opposite the handle, the casing is provided with a constricted cylindrical chamber 6 having movably disposed therein a tool holder or anvil 7 that has an impact surface 17 which projects toward a 70 similar surface 18 on the hammer head 1. In order that the anvil 7 may not bear rigidly against the end of the casing 3, a spring 5 is interposed therebetween within the chamber 6.

75 The anvil 7 carries a suitable impact tool, such as a chisel 8, that projects through an opening 9 in the bottom of the hammer casing 3 toward the work piece 10 to which it is to be applied.

80 The hammer head 1 is held, under pressure, against the anvil 7 by means of a compression spring 11 which reacts against a spring rest 12 that is held by the upper end wall of the casing 3. The spring rest 12 is adjustable in an axial direction by means of an adjusting screw 13 to permit variation of the compressive forces that may be applied to the spring 11 to change the force which biases the hammer head 1 against the impact surface 17 of 85 the anvil 7 when the hammer is at rest.

85 The hammer is supplied with power by means of a solenoid 14 that is disposed around the non-magnetic guiding member 2 for the magnetizable hammer head 1. It may readily 100

be seen that the hammer head 1 operates as an armature or plunger for the solenoid 14. When the solenoid is energized, the plunger or hammer head 1 is withdrawn from the anvil 7, thereby compressing the spring 11 and storing potential energy therein which is subsequently transmitted to the hammer head 1 as kinetic energy and released in an impact upon the anvil 7. Energization of the solenoid 14 is usually effected by means of an alternating current, although the hammer may be operated by means of any periodically interrupted electric current. In the embodiment of the invention illustrated, conductors 15 are provided for connecting the solenoid 14 to a suitable power source.

When the hammer shown in Fig. 1 is energized from a source of alternating electric current, such as a 60-cycle current, the magnetic flux induced by the solenoid 14 exerts a periodic force upon the plunger or hammer head 1 tending to pull it toward the center of the solenoid twice during every cycle of the current. Thus, it is evident that the solenoid 14 exerts 120 force impulses per second, upon the hammer head 1 in a direction away from the anvil 7 and against the action of the spring 11. The magnetic and spring forces so acting upon the plunger may be considered as being equivalent to an alternating force pulling the hammer head away from the anvil and subsequently projecting it toward the same.

In analyzing the operation of the hammer device, it is desirable to deal with an alternating force rather than with a pulsatory force acting upon the movable hammer head. Accordingly, I shall hereinafter consider the initial spring pressure as a resultant of the actual initial spring compression and the average value of the unidirectional component of the pulsating force acting upon the hammer head. The force acting upon the hammer head or plunger may then be considered as being an alternating force, and, in the idealized conditions, the alternating force may be assumed to be a pure harmonic force. Such assumption will not, in any way, disturb the results and the conclusions derived from the analysis, since, for practical purposes, it is sufficient to consider only the major harmonic component of the force acting upon the hammer head and to neglect the influence of the minor harmonic components.

In the hammer device shown in Fig. 2, the essential elements of the mechanical hammer system are the same as those in Fig. 1, except that the magnetic force exerted upon the hammer head 1 is of an alternating character instead of a unidirectional pulsatory character. The alternating force is obtained by means of two solenoids 21 and 22 placed at different positions with respect to the length of the hammer casing and alternately energized, by means of two rectifiers 24 and

25 (Fig. 3), from an alternating-current source 26. By utilizing the construction shown in Figs. 2 and 3, the frequency of the force acting upon the hammer head 1 is made equal to the frequency of the alternating-current.

Referring now to Fig. 4 the mechanical oscillating system, which is diagrammatically represented therein, comprises a hammer head 1 that is assumed to embody the entire mass of the system and a substantially weightless spring 11 that constitutes the resilient member. The hammer head 1 is assumed to be mounted for reciprocal motion without friction along a hammer axis X—X that is inclined at an angle b to the horizontal. The angle b represents the inclination of the hammer with the earth's surface when it is in actual use.

At the upper end of the hammer axis X—X, a spring rest 12, that is assumed to be perfectly rigid, is provided for resisting the reaction of the spring 11.

The motion of the hammer head 1 is limited, in the downward direction, by an anvil 7 that is also assumed to be perfectly rigid but is supposed to be able to absorb a certain amount of energy from each impact of the hammer head 1.

It will readily be seen that this mechanical system constitutes an oscillating or vibrating system of one degree of freedom that has a definite natural period of vibration which depends upon the mass of the hammer head 1, the resilience of the spring 11 and the manner in which they are mounted.

It will be further assumed that the resultant of the forces imparted to the hammer head 1 by the solenoid 14 or the solenoids 21 and 22 shown in Figs. 1 and 2 or by other means is a simple harmonic vibratory force that may be represented by the projection on the hammer axis of a force vector F that rotates at a uniform angular velocity in a plane containing the hammer axis X—X.

The hammer may be adjusted to deliver blows at a frequency which is a certain fraction of the frequency of the applied force.

For example, if the hammer shown in Fig. 1 is utilized with standard 60 cycle current, the solenoid 14 will exert 120 force impulses per second upon the hammer head, as explained hereinbefore. Under these circumstances, it is possible to make the hammer head strike against the anvil 120, 60, 40, etc., times per second, corresponding to 1, 2, 3, etc., force cycles per blow. The mode of operation then may be said to be 1, 2, 3, etc.

The natural frequency of oscillation of the hammer head, when its motion is not obstructed by the anvil, and the initial compression of the spring determine the mode of operation.

The energy that is imparted to the hammer head 1 by the impressed magnetic force is

partially absorbed by the anvil 7 and, therefore, the velocity of the hammer head, as it rebounds from the anvil, is correspondingly less than the impinging velocity.

5 During the upward stroke of the hammer head, sufficient energy is stored in the spring 11 to insure that the required impinging velocity will be developed during the downward stroke.

10 The particular condition under which a hammer embodying the invention will operate most effectively and the method of proportioning the various parts thereof to obtain the exact relationship between the natural frequency of oscillation of the hammer head, the initial compression of the spring and the mode of operation, will be more fully set forth in the following mathematical consideration.

15 In expressing the mathematical relations leading up to the principle of operation of my device I shall use the following notations:

Weight of the hammer head W

Mass of the hammer head M

Scale of the spring or the resisting force

20 per unit deformation k

Angular velocity of rotation of the force vector u

Angular velocity corresponding to the natural frequency of the hammer head when 25 its motion is not obstructed by the anvil u_n

Amplitude of forced oscillations of the hammer head when its motion is not obstructed by the anvil a

30 Specific speed q

Mode of operation or the number of force cycles per blow n

Angular position of the force vector at the moment of impact G

Auxiliary angles G_0, G_1 and G_2

40 Initial compression of the spring x_0'

Compression of the spring corresponding to the component of gravity and the constant part of the pulsating force x_0''

Equivalent initial compression of the 45 spring x_0

Spring function S

Speed function R

50 Referring to Fig. 4, the alternating force acting upon the hammer head 1 may be represented by a force vector F that rotates at a uniform angular velocity u and exerts a harmonic component in the direction of the hammer axis X—X. This harmonic component may be expressed as a sine function of

55 the force F having a periodicity of u .

The condition of equilibrium, for the forces acting upon the hammer head at the time t after the force vector points in the negative x -direction, when the head has moved a distance x , from the anvil, is given by the equation

$$M \frac{d^2x}{dt^2} + k(x_0' + x) + W \sin b = -F \cos ut \quad (1)$$

The effect of the weight of the hammer head 1 may be expressed by the corresponding displacement or compression x_0'' of the spring, thus

$$\frac{W \sin b}{k} = x_0'' \quad (2)$$

Thus if x_0 is introduced as representing an equivalent spring compression, where

$$x_0 = x_0' + x_0'' \quad (3)$$

The equation of motion may be written

$$M \frac{d^2x}{dt^2} + k(x_0 + x) = -F \cos ut \quad (4)$$

As pointed out hereinbefore, where the applied force is of a pulsating character instead of an oscillatory character, the unidirectional component of such force may also be represented by a corresponding spring compression, and it may be embodied in the equivalent initial spring compression x_0 of equation (3).

The solution of equation (4) is

$$x + x_0 = A \cos u_n t + B \sin u_n t \quad (5)$$

$$\frac{F}{k - Mu^2} \cos ut$$

The quantity u_n represents the angular velocity corresponding to the natural frequency of oscillation of the hammer head 1, when its motion is not obstructed by the anvil 7 and has the value

$$u_n = \sqrt{\frac{k}{M}} \quad (6)$$

The specific speed q is defined as the ratio of the actual angular velocity of the force vector to u_n , thus

$$q = \frac{u}{u_n}$$

also

$$a = -\frac{F}{k - Mu^2} = \frac{F}{Mu^2} \frac{q^2}{q^2 - 1} \quad (7)$$

The quantity a represents the amplitude of oscillation of the hammer head 1 under influence of the force F , when its motion is not obstructed by the anvil 7. With the introduction of q and a the solution may be written in the following form:

$$x + x_0 = A \cos \frac{ut}{q} + B \sin \frac{ut}{q} + a \cos ut \quad (8)$$

The solution contains two arbitrary constants of integration A and B which are determined from the initial circumstances of the motion at the moment of impact. At that moment, the hammer head 1 is just leaving the anvil 7 after a blow, and the force vector makes an angle G with the negative x -axis. Thus

$$x = 0 \quad ut = G \quad (9)$$

The hammer head is leaving the anvil with a certain velocity v_1 , that is,

$$\frac{dx}{dt} = v_1 \quad ut = G \quad (10)$$

These two conditions are sufficient to determine the constants of integration, but they will be expressed in terms of the velocity v_1 and the angle G which, so far, are undetermined.

In order to obtain a continuous succession of blows of the same character, each "blow cycle," or complete reciprocation of the hammer head, should contain an integral number n of force cycles. This number will be referred to as the mode of operation. Consequently, at the conclusion of the blow cycle, the hammer head should again touch the anvil, that is

$$x=0 \quad ut=2\pi n+G \quad (11)$$

By introducing the conditions (9), (10) and (11) into equation (8) and its derivations we obtain the following equations

$$x_0 = A \cos \frac{ut}{q} + B \sin \frac{ut}{q} + a \cos G \quad (12)$$

$$\frac{v_1}{u} = -A \sin \frac{ut}{q} + B \cos \frac{ut}{q} - aq \sin G \quad (13)$$

$$x_0 = A \cos \frac{2\pi n+G}{q} + B \sin \frac{2\pi n+G}{q} + a \cos G \quad (14)$$

These equations give the following values for the integration constants A and B.

$$A = \left(\frac{v_1}{u} q + aq \sin G \right) \frac{\cos \frac{\pi n+G}{q}}{\sin \frac{\pi n}{q}} \quad (15)$$

$$B = \left(\frac{v_1}{u} q + aq \sin G \right) \frac{\sin \frac{\pi n+G}{q}}{\sin \frac{\pi n}{q}} \quad (16)$$

and, for the determination of the angle G

$$x_0 - a \cos G = \left(\frac{v_1}{u} q + aq \sin G \right) \cot \frac{\pi n}{q} \quad (17)$$

The displacement and the velocity of the hammer head are now

$$(x + x_0) = (x_0 - a \cos G) \frac{\cos \frac{\pi n+G-u}{q}}{\cos \frac{\pi n}{q}} + a \cos ut \quad (18)$$

$$\frac{dx}{dt} = (v_1 + au \sin G) \frac{\sin \frac{\pi n+G-ut}{q}}{\sin \frac{\pi n}{q}} - au \sin ut \quad (19)$$

The velocity with which the head strikes the anvil is now obtained from equation (19) by putting $ut=2\pi n+G$. This velocity will be denoted by $-v_2$, being directed in the negative direction of x. We obtain

$$v_2 - v_1 = 2au \sin G \quad (20)$$

The first requirement for sustained and efficient operation is that the increase in the velocity of the hammer head between blows, $v_2 - v_1$, shall be positive. Now, the quantity a , equation (7), is positive if q is greater than 1, that is, if the hammer operates above the natural frequency of the hammer head, but it is negative if q is less than 1, that is, when the hammer operates below the natural frequency of the hammer head. Consequently, the angle G must not vary beyond the following limits

$$q > 1 \quad 0 < G < \pi \quad (21)$$

$$q < 1 \quad \pi < G < 2\pi \quad (22)$$

At each impact of the hammer head upon the anvil, a certain amount of energy is dissipated in the form of work done by the tool. The impact reduces the impinging velocity v_2 of the hammer, and, if this dissipation is complete, there will be no rebound, that is, v_1 will be equal to zero. Usually, all the energy latent in the blow is not dissipated, so that the return velocity v_1 will have a small value which is expressed

$$v_1 = e v_2 \quad (23)$$

The constant e being a coefficient of restitution dependent upon the efficiency with which the tool is working. It is evident that e depends not only upon the tool itself, but also upon the support of the working piece and other factors. With the introduction of the coefficient of restitution, I can express v_1 and v_2 separately and find that

$$v_1 = \frac{2e}{1-e} au \sin G \quad (24)$$

$$v_2 = \frac{2}{1-e} au \sin G \quad (25)$$

Consequently the energy E dissipated in one blow may be expressed as

$$E = \frac{1}{2} M(v_2^2 - v_1^2) = 2 \frac{1+e}{1-e} a^2 u^2 \sin^2 G \quad (26)$$

120

125

130

The determination of the impact angle G from equation (17) gives

$$R \sin G + \cos G = S \quad (27)$$

when

$$R = \frac{1+e}{1-e} q \cot \frac{\pi n}{q} \quad (28)$$

$$S = \frac{x_0}{a} \quad (29)$$

10 The quantity R is denoted as a speed function since it is principally dependent upon the specific speed q . The quantity S is denoted as a spring function since it is primarily dependent upon the compressions of the spring x_0 .

To facilitate the solution of (27) we introduce two angles G_1 and G_2 , determined by

$$20 \quad \begin{aligned} \sin G_1 &= \frac{1}{\sqrt{1+R^2}} & \cos G_1 &= \frac{R}{\sqrt{1+R^2}} \\ & & \sin G_2 &= \frac{S}{\sqrt{1+R^2}} \end{aligned} \quad (30)$$

25 whereupon equation (27) becomes

$$\sin(G + G_1) = \sin G_2 \quad (31)$$

This equation in G has two roots

$$30 \quad G = G_2 - G_1 \text{ and } G = \pi - G_1 - G_2 \quad (32)$$

A sustained sequence of operating cycles is possible only if the quantities S and R are so adjusted that these two roots are identical.

35 This is possible only if

$$S = \pm \sqrt{1+R^2} \quad (33)$$

and then the angle G_2 assumes the value $\frac{\pi}{2}$

40 G_0 denotes the special positive or negative value that G_1 assumes when R is positive, that is,

$$G_0 = \cot^{-1} R \quad (34)$$

45 Equation (33) expresses the second requirement for sustained operation, and I shall now deduce from this requirement, and the one previously found, in equations (21) and (22), the physical design proportions of 50 the hammer, to which they correspond.

The values of the angle G , which are obtained from equation (32), depend upon the sign of the spring function S and of the speed function R .

55 The quantity S derives its sign from both x_0 and a . Theoretically, both of these may be either positive or negative, but, since there are certain practical difficulties in arranging springs of this kind for alternating tension and compression, I disregard the possibility of negative values of x_0 , so that the sign of S will be the same as that of a . Consequently, S will be positive when q is greater than one and negative when q is less than one.

60 The quantity R may be assumed tempora-

rily to have both positive and negative values, depending upon the value of $\cot \frac{\pi n}{q}$.

70 Four possible combinations are thus obtained, to each of which correspond a certain value of the angle G . These combinations are

$$(a) R > 0 \text{ and } S > 0, q > 1 \quad 75$$

$$G = \frac{\pi}{2} - G_0 \quad (35)$$

$$(b) R > 0 \text{ and } S < 0, q < 1 \quad 80$$

$$G = -\left(\frac{\pi}{2} + G_0\right) \quad (36)$$

$$(c) R < 0 \text{ and } S > 0, q > 1 \quad 85$$

$$G = -\left(\frac{\pi}{2} - G_0\right) \quad (37)$$

$$(d) R < 0 \text{ and } S < 0, q < 1 \quad 90$$

$$G = \frac{\pi}{2} + G_0 \quad (38)$$

95 Now referring to the conditions already established in equations (21) and (22), I find that cases (c) and (d) do not represent possible operating conditions, because they conflict with this requirement. For this reason, operation of the hammer is restricted to positive values of the speed function R , that is, $\cot \frac{\pi n}{q}$

100 must always remain positive, so that there are two ranges of values for the argument

$$105 \quad \left. \begin{aligned} 0 &\leq \frac{\pi n}{q} < \frac{\pi}{2} & \text{or} & \frac{\pi}{2} < \frac{\pi n}{q} < \frac{3\pi}{2} \\ 2\pi &= \frac{\pi n}{q} = \frac{\pi}{2} & & 3\pi = \frac{\pi n}{q} = \frac{7\pi}{2} \end{aligned} \right\} \quad (39)$$

110 etc., etc.

I thus obtain a sequence of possible values of the specific speed q

$$115 \quad q = 2n \text{ to } \infty \quad (40)$$

$$120 \quad \left. \begin{aligned} q &= \frac{2}{3}n \text{ to } n \\ q &= \frac{2}{5}n \text{ to } \frac{n}{2} \\ q &= \frac{2}{7}n \text{ to } \frac{n}{3} \end{aligned} \right\} \quad (41)$$

etc.

125 Sustained operation is always possible for values of the specific speed above $2n$. No operation can take place between n and $2n$, but below n there is a series of narrow strips within which sustained operation is theoretically possible. These are restricted to spe-

cific modes, however, because of the exclusion of cases (c) and (d) of the possible solutions, equations (36).

For the different modes of operation (n) the following possible ranges for the specific speed q are obtained.

$$n=1 \quad q=2 \text{ to } \infty \text{ when } S>0$$

$$n=1 \quad q=\frac{2}{3} \text{ to } 1, \frac{2}{5} \text{ to } \frac{1}{2} \text{ etc., when } S<0$$

$$n=2 \quad q=4 \text{ to } \infty, \frac{4}{3} \text{ to } 2 \text{ when } S>0$$

$$n=2 \quad q=\frac{4}{5} \text{ to } 1, \frac{4}{7} \text{ to } \frac{2}{3} \text{ etc., when } S<0$$

It may be seen from this that the narrow speed ranges are only partially useful. With this fact in view the first range $q=2n$ to ∞ denotes the main speed range.

This relationship is shown in Fig. 5 where-
in the ordinate represents the specific speed q and the abscissa represents the mode of operation n . The upper speed range, ex-
tending upward to infinite values of q , is
25 bounded by the line 31. The next speed
range is bounded by the lines 32 and 33, the
next by the lines 34 and 35, and so on.

The main speed range represents only the possible values that q and n may assume. To determine for any specific case, the correct value of q for a certain mode and for certain proportions of the hammer, resort may be had to equation (33). This can be written in the following form.

$$35 \quad S = \frac{x_0}{a} = \pm \sqrt{1 + \left(\frac{1+e}{1-e} q \cot \frac{\pi n}{q} \right)^2} \quad (42)$$

The equation represents the relation between all design variables of the device, expressed more or less directly through the quantities S , x_0 , a and q , which must hold if sustained operation is to be obtained.

Referring to Fig. 6, the graph shown is of some of the characteristic curves of the per-
cussive device for various conditions of op-
eration within the main speed range.

In this graph, the specific speed q is re-
presented by the abscissa and the spring func-
tion S and phase angle G are represented
50 by the ordinates. Line 36 shows the ratio be-
tween the equivalent initial compression of
the spring x_0 and the amplitude of free vi-
bration of the hammer head, which must exist
55 in order to attain a sustained sequence of
blows in the first mode, when the coefficient
of rebound is zero. Line 37 shows the same
relation when the coefficient of rebound e is
20. Lines 38 and 39 show the same relations
for the second mode, that is, when the force
60 completes two cycles for each blow and lines
40 and 41 show the same relations for the third
mode. Similar curves can be drawn for
other modes.

To obtain the actual relations of the masses
65 and the springs to attain these conditions it

is merely necessary to introduce the values of x_0 and a , from equations (2) and (7).

The values of the impact or phase angle G that are obtained for the first mode of operation and for values of the coefficient of rebound of zero and two tenths are shown by the lines 42 and 43, respectively. The lines 44 and 45 show the values of G for the second mode of operation when the coefficient of rebound is equal to zero and two tenths, and the lines 46 and 47 show these values for the third mode of operation.

The effectiveness of performance of the de-
vice is greatly dependent upon this impact
angle, because the impact velocity v_2 varies
80 with the sine of this angle.

It is evident to those skilled in the art that
the foregoing conclusions will hold for me-
chanical arrangements different from those
illustrated. For example, the force F may be
85 a function of the speed and may be produced
by means other than electromagnetic coils,
in which case, it is merely necessary to change
the expression for a , equation (7). The
curves in Fig. 6 will remain unchanged, ex-
cept for the units in which they are expressed.
The particular arrangement and proportions
90 of the various cooperating parts of the per-
cussive device embodying the invention may
be materially changed without departing
from the spirit and scope of the invention
95 as defined in the appended claims.

I claim as my invention:

1. In a percussive device, the combination
with a tool-supporting anvil, of a hammer
100 head disposed to impinge against the anvil,
means for applying a periodic force to actuate
the hammer head, and a member offering
elastic resistance to the motion of the hammer
head away from the anvil, said elastic mem-
ber and the hammer head being so proportioned
105 that the hammer will operate with a
stroke frequency which is a sub-multiple of
the periodic force.

2. In a percussive device, the combination
with a tool-supporting anvil, of a hammer
110 head disposed to impinge against the anvil,
means for applying a periodic force to actuate
the hammer head, and a member offering
elastic resistance to the motion of the hammer
head away from the anvil, the natural fre-
115 quency of the hammer head and the mini-
mum pressure of the elastic member being
proportioned in such manner that the ham-
mer will operate when there are two or more
120 cycles of the periodic force for each blow of
the hammer head.

3. In a percussive device, the combination
with a tool-supporting anvil, of an oscillating
125 system comprising a hammer head disposed
to strike said anvil and a resilient member,
and means for applying a periodic force to
said hammer head to operate it, said oscillat-
ing system being so proportioned that the de-

vice will operate at a frequency different from that of the applied periodic force.

4. In a percussive device, the combination with a tool-supporting anvil, of an oscillating system comprising a hammer head disposed to impinge upon said anvil and a resilient member, and means for applying a periodic force to said hammer head to cause it to oscillate, said anvil, hammer head and resilient member being so proportioned that a periodic force having a frequency that is a harmonic of the frequency at which the oscillating system is adjusted to operate will cause the percussive device to function.

5. In an electrically driven percussive device, the combination with an anvil for supporting a tool, of a solenoid for exerting periodic magnetic impulses and a mechanical oscillating system comprising a hammer head of magnetizable material that is disposed to impinge upon the anvil and to constitute an armature for the solenoid and a resilient element, said oscillating system being so proportioned that it will vibrate at the frequency of one harmonic of the impressed magnetic impulses.

6. In an electrically driven percussive device, the combination with a tool-supporting anvil, of an oscillating system comprising a resilient member and a hammer head of magnetizable material disposed to impinge upon the anvil and a solenoid for impressing periodic magnetic impulses upon the hammer head, said oscillating system being so proportioned that the device will operate when the frequency of said impulses is a multiple of the resulting frequency of vibration of the oscillating system.

7. In a percussive device, a reciprocating hammer mass, yielding energy-storing means constituting, with said mass, a mechanical oscillating system and tending to cause said mass to strike in one direction of the reciprocal movement thereof, and means for exercising upon said mass, a cyclic force producing such reciprocal movement, the several elements of said device being so related that the device will operate when there are two or more force cycles for each hammer stroke.

8. A percussive device comprising a hammer body, a relatively stationary guide permitting motion of said body toward an object to be struck and away therefrom, yielding energy-storing means supported by said guide and pressing said body toward said object, space-energizing means producing an intermittent force causing said body to cyclically move away from said object and strike the same, the body, the energy-storing means and the force being so related to each other that the hammer will operate when there are at least two force cycles for each hammer stroke.

9. A percussive device comprising a hammer body, a relatively stationary guide per-

mitting motion of said body toward an object to be struck and away therefrom, yielding energy-storing means supported by said guide and pressing said body toward said object, electrical space energizing means supported by said guide and impressing upon said body a cyclical force causing the device to operate with a cyclical striking action of said body, said hammer body and energy-storing means being so proportioned that the frequency of said striking action is a fraction of the force frequency.

10. In a reciprocating device, a mechanical oscillating system comprising a resilient member and a plunger of predetermined mass, a solenoid disposed to exert magnetic impulses upon the plunger and a source of alternating electric current of standard frequency for energizing the solenoid, said oscillating system being so designed that the device will operate at a frequency of oscillation which is a sub-multiple of the frequency of the energizing alternating current.

11. In a percussive device, in combination, a tool supporting anvil, a hammer disposed to impinge upon the anvil, a resilient element disposed to exert force upon the hammer in the direction of the anvil, said hammer and resilient element comprising a mechanical oscillating system, and means for impressing a substantially harmonic oscillating force upon the hammer, the mass of said hammer and the characteristic of said resilient element being so chosen that the hammer will operate at a frequency which is a sub-multiple of the frequency of the impressed oscillating force.

In testimony whereof, I have hereunto subscribed my name this 20th day of July, 1927.

CARL RICHARD SODERBERG.
